HEAT EXCHANGE APPARATUS FOR LIQUIDS
CONTAINING SOLIDS

William M. Bready, Milwaukee, Wis.

Application November 4, 1949, Serial No. 125,442

14 Claims. (Cl. 257—247)

1 This invention relates to heat exchange apparatus for liquids containing solids.

It is a primary object of the invention to obtain high efficiency of heat transfer notwithstanding that one of the liquids involved in the transfer of heat may be carrying large quantities of foreign matter, such as would clog any conventional heat exchanger. To obtain high efficiency of heat transfer, a high velocity of flow is desirable. The required velocities may be achieved only if the passages through which the flow occurs are of restricted capacity in proportion to the amount of liquid handled. The present invention provides a heat exchange apparatus in which, throughout the various sections of the apparatus, flow occurs at high velocity through parallel tubes of small cross section, stoppages being precluded by the uniformity of such cross section and the absence of any shoulders against which foreign matter may lodge. It is a very important feature of the apparatus disclosed that where the liquid is admitted and divided to pass through the multiple tubes of heat exchanger sections, means is provided for backwash so that any accumulations of solids at this point can be discharged before stoppages occur.

Cross reference is made to my co-pending application Serial No. 365,819, filed July 3, 1953, and entitled Heat Exchange Apparatus for Liquids Containing Solids.

The foregoing and other objects of the invention will be more apparent from the following disclosure thereof with reference to the accompanying drawings, wherein:

Fig. 1 is a view in side elevation and partially in section showing apparatus embodying the invention.

Fig. 2 is a detail view in enlarged axial section through one of the heat exchanger inlets.

Fig. 3 is a fragmentary detail view taken in section through a portion of the heat exchanger.

Fig. 4 is a detail view in perspective of one of the connectors between heat exchanger sections.

Fig. 5 is a fragmentary side elevation of a modified embodiment of the heat exchanger arranged for automatic backwashing.

Fig. 6 is a view in end elevation of the device shown in Fig. 5.

Fig. 7 is an enlarged detail view in front elevation of the backwash control valve and its operating mechanism.

Fig. 8 is a further enlarged detail view in transverse section through the control valve.

2 Fig. 9 is a view in side elevation showing a further modified form of the heat exchanger.

Fig. 10 is a diagrammatic view in side elevation showing the connections of my improved heat-exchanger for special uses.

For purposes of exemplification, the device is illustrated for laundry use, where the hot waste water, entering the heat exchanger at approximately 160°, gives off its heat to clear water entering the exchanger at 40° F. The waste water temperature at the point of discharge has been reduced from 160° F. to 60° F., and the fresh water temperature has been increased from 40° F. to approximately 140° F.

15 The installation of such a device in a laundry reduces fuel costs approximately a third and makes about the same percentage increase in available boiler capacity. However, in a laundry, the waste water is extremely difficult to handle without stoppages, since it contains not only such foreign material as buttons and the like which can be eliminated by screens, but also a large amount of such foreign material as lint which passes through the screens into the heat exchanger.

20 In the installation shown, the usual sump 10 is provided below the level of the laundry floor 11. Into this sump, through the pipe 12, is led all of the waste water from the washing machines.

25 Such water usually enters through the aperture 13 into a removable screen receptacle 14 which traps most of the foreign matter. The remaining water, with considerable lint, issues through the top screening wall 15 of receptacle 14 and is picked up by one of the intake pipes 16 leading to the motor driven pump 17.

30 The pump outlet pipe 18 is desirably equipped with a pressure gauge 19 and thermometer 20. It is coupled through valves 21 and 22 to the respective terminals 23, 24 of a heat exchanger which comprises any desired number of jacket pipes 25, 26, 27, 28, 29, 30, through which the hot waste water passes in parallel copper tubes 31, such as those shown in Fig. 2.

35 40 45 Each jacket pipe 26 desirably has a terminal flange 32 at each of its ends. The flanges may conveniently be welded to the pipes. A closure disk 33, preferably registering with the flange 32 and in face contact therewith, supports the ends of the tubes 31, being provided with apertures in which the respective tubes are fixed. Thus, each tube extends rectilinearly through the jacket pipe 26 in spaced relation to the pipe and to the other tubes. As best shown in Figs. 55 2 and 3, the tube ends may project slightly

beyond the outer face of the closure disk 33 wherein they are mounted.

Co-acting with closure disk 33 is another flange or disk. Fig. 2 shows at 34 a terminal flange on fitting 23. In each of the intermediate couplings, as shown in Fig. 3, there is a disk at 35 which supports a series of elbowed tubes 36 in registry with the ends of tubes 31, the corresponding ends of tubes 36 being preferably slightly countersunk in the supporting disk 35 so that, when the disks 33 and 35 are assembled, the ends of the respective straight and elbowed tubes will be in substantial abutting contact. In each case, an annular series of bolts 37 passes through registering openings in the flanges and disks to maintain them in assembly. Connections between the heat exchange tubes of the various heat exchanger sections are made in like manner.

Heat exchanger jacket pipe 25 and heat exchanger jacket pipe 30 are respectively provided with external connections at 38 and 39. At the end opposite the external connection 38, jacket pipe 25 has a coupling 40 which connects it with jacket pipe 26. At the opposite end of jacket pipe 26, a coupling 41 connects jacket pipe 26 with jacket pipe 27. Similarly, there is a connection at 42 between jacket pipes 27 and 28, a coupling at 43 between jacket pipe 28 and jacket pipe 29, and a coupling at 44 between jacket pipe 29 and jacket pipe 30, the latter being at the end of jacket pipe 30 remote from its external pipe connection 39.

Between the valve 21 and the fitting 23 there is a pipe connection through valve 45 to an outlet pipe 46 which leads to a waste pipe 47. The outlet pipe 46 may be provided with a thermometer at 48, and it has a connection through valve 49 with the heat exchanger fitting 24.

With valves 22 and 45 closed, water pumped from the sump 10 will pass upwardly through valve 21 and fitting 23 into the heat exchanger tubes 31 in the first heat exchanger jacket pipe 25. Thence, it will flow in parallel through such tubes and through the corresponding elbowed tubes and the heat exchanger tubes of successive sections of the heat exchanger until it issues through fitting 24 and valve 49 to pass to waste through pipe 46 and waste pipe 47.

It will be observed that the means of assembly as herein disclosed conveniently provides readily assembled and disassembled butt connections between the successive tubes traversed throughout the heat exchanger system so that there are no pockets or exposed raw edges upon which lint carried by the water might catch and build up. Each sequence of tubes is interiorly smooth and of continuously constant cross section. The individual tubes being small in diameter, the liquid is forced to travel through the system at high velocities, scouring the interior tube walls and thereby assuring heat transfer with high efficiency through the tube walls into the liquid contained in the jackets.

In the meantime, fresh water to supply the laundry washing machines is entering through the external pipe connection at 39 and passing in counterflow to the waste water through the series of jackets from jacket 30 to jacket 25, passing through pipe 38 to the point of use.

In such a system, the only place where stoppages may develop due to the deposit of lint or other foreign matter is at the point where the fitting 23 provides communication between the relatively large cross sectional supply line and

the parallel and small diameter tubes of the heat exchanger. To preclude the development of stoppages in fitting 23, the control valves are periodically reversed to backwash this fitting, the valves 22 and 45 being opened, and valves 21 and 49 closed. This immediately discharges through valve 45 to the sewer any lint which may have accumulated against the disk 33. Since very little time is required for backwashing, and since it is less desirable to have concurrent flow through the heat exchanger than to have counter-flow therethrough, the valves will ordinarily be left only briefly in the backwashing position and will thereupon be re-set to their original positions for counterflow. Obviously, the valves may be left in positions for concurrent flow if desired or, if it be desired that the fresh water enter at the top through pipe 38 and issue from the bottom through pipe 39, counter-flow may be achieved by simply setting the valves in a reverse position from that originally described, valves 22 and 45 being open, and valves 21 and 49 closed during the period of normal operation.

It is also possible to re-arrange the tubes within the jackets so that a given set of tubes will extend forth and back with integral elbows as shown in Fig. 9. In this construction, the jacket pipes 50, 51 and 52 may be made exactly as above described, being provided with the terminal flanges 32 already mentioned. The header disk 53, however, is provided with elbowed tubes 54 which curve upwardly and elbowed tubes 55 which curve downwardly. The tubes within jacket 50 with which elbowed tubes 54 connect are extended through the jacket to elbowed tubes 56 mounted on header disk 57 and communicating with those tubes in jacket 50 with which elbowed tubes 55 connect. Thus, assuming there are six tubes within the jacket, three of these would be connected in series to three others, so that there would be three lines of tubes extending forth and back through any given jacket, similar connections being made to the other jackets in the series.

Instead of making the valve control manual, as above described in connection with Fig. 1, the control may be automatic as suggested in Figs. 5, 6, 7 and 8. Figs. 5 and 6 also suggest a somewhat different arrangement of the heat exchanger sections, which is more compact in a vertical direction and which facilitates the application of the four-way valve disclosed in Figs. 5 to 8. It will, however, be understood that these features are separate and not interdependent, either the compact arrangement of the heat exchanger sections or the automatic control being independently usable without the other.

In the arrangement of Figs. 5 to 8, the heat exchanger sections 25, 25, 27, 28, 29 and 30 may be assumed to be identical in every way with those shown in Fig. 1 except that they are arranged in two tiers of three each instead of a single tier of six sections, the connection between sections 27 and 28 being horizontal. The fittings 230 and 240, corresponding to fittings 23 and 24 of Fig. 1, may comprise elbows communicating with passages 66, 67 at the sides of a four-way valve casing 68. Other passages 69 and 70 of such casing lead respectively to the pump line 180 and the waste line 460, these corresponding respectively to pipes 18 and 46 of Fig. 1.

Within the valve casing 68 there is rotatably mounted a valve plug 75 having a pair of ninety-degree ducts 76 and 77 designed, as shown in

Fig. 8, to provide communication between pairs of ports which are angularly proximate. As illustrated, the passage 76 provides communication between ports 66 and 69, while the passage 77 simultaneously provides communication between the ports 67 and 70. A ninety-degree rotation of the plug 75 will place ports 67 and 69 in communication with each other and will simultaneously place ports 66 and 70 in communication with each other. The stem of the rotary valve plug 75 projects at 78 and carries a segmental gear 79 meshing with reciprocable rack 80. This rack is attached to a piston 81 movable in an air cylinder 82 with which air tubes 83, 84 communicate. These tubes, in turn, are operated by a four-way valve 85 similar in construction to that already described, and having air supply connections at 86 and an air exhaust at 87. This valve has a control lever 88 operated in one direction by spring 89 and in the other by solenoid 90 energized from time to time by a time switch 91. The spring normally holds valve 85 in a position to apply air below piston 81 to hold valve plug 75 in the position shown, wherein waste water flows from pipe 180 through passage 76 and port 66 to heat exchanger section 25 and is discharged from section 30 through passage 77 to waste pipe 460.

The described arrangement is merely a convenient means of using electrical controls and pneumatic power supply from time to time to actuate the rotary valve plug 75 for reversing flow to backwash the coupling 230 by delivering water from the pump through pipe 180 and passage 76 to port 67, whereby the waste water first enters heat exchanger section 30 and passes thence through the other sections to section 25, from which the water issues through valve plug passage 77 to port 70 and drainpipe 460. As already described, this backwashing arrangement will ordinarily continue for only a relatively small proportion of the time, the waste water being directed through the heat exchanger for the greater proportion of the time in counter-flow to the direction in which the newly arrived water is passing through the jackets.

Fig. 10 diagrammatically illustrates a specialized application of a heat exchanger embodying this invention to distillery practice. Although the heat exchanger is greatly simplified in the diagrammatic showing, it will be understood to incorporate the continuous multi-tube flow as above described to promote a high coefficient of heat transfer. In distillery practice, the heat exchanger is used primarily for cooling the mash and, incidentally, for mixing the proper amount of slop with mash to get an approximate 80-20 mixture (eighty per-cent mash, twenty per-cent slop). The disclosure exemplifies how the efficient heat transfer achieved by reason of multi-tube flow is used for cooling just as effectively as for heating, and it works with highly viscous semi-liquids, such as mash.

In distillery practice, the required cooling of a given quantity of slop has been accomplished in one and one-half hours through the use of this heat exchanger at 25-40 pounds pumping pressure, as compared with four and one-half hours required for the cooling of the same amount of material at 120-150 pounds pumping pressure according to previously existing practices. The reduction in the required cooling period is accomplished with only fifty per-cent of the volume of cooling water at forty per-cent of the previous flow rate. At the same time, the yield of alcohol

from grain was increased because of the cooling efficiency and because the disclosed arrangement is more readily maintained sterile, and pockets wherein secondary fermentation has previously occurred are eliminated through the use of this apparatus.

There are many other advantages such as the provision of a supply of "topping off water" to complete the volume fill of the fermentation tanks; the facility of steam sterilization; and the adaptability for positive mechanical controls.

In such a distillery installation, the jackets 92 and 93 are typical of any desired number of heat exchange sections, the tubes 94 and 95 being in continuous connection through the respective jackets in multi-tube or parallel arrangement as already described. The incoming mash is supplied through a pipe 96 and subdivided at a header connection to enter the tubes of jackets 93. The mash may have, for example, a temperature of 146° F. The incoming slop is supplied through pipe 98 connected by header 980 to the parallel tubes of jackets 92.

It is common practice to innoculate the incoming mash with approximately twenty per-cent by volume of slop, but the slop must first be reduced to an appropriate temperature. By way of example, the slop may be assumed to enter through pipe 98 at 190° F. and to leave the multiple tubes 94 of jackets 92 through pipe 99 at a temperature of 110° F., having been cooled by water supplied through pipe 100, valve 101, and pipe 102 at an assumed temperature of 60°. The unneeded slop is discharged to waste through pipe 103, and the valve 104 is used to regulate the admission to the mash line 96 of the desired proportion of innoculating slop through the cross connection 105. If somewhat less cooling of the slop is desired prior to inoculation, water at a temperature of approximately 100° may be supplied through pipe 102 to the jackets 92, by closing valve 101 and adjusting valve 106 to use water which has already passed through jackets 93. The cooling water for jackets 93 is taken from pipe 100 subject to the control of valve 107 through pipe 108, and it issues from the serially connected jackets 93 through pipe 109 to valve 106, whereby it may be passed to the drain pipe 110 or to pipe 102, as is desired.

The mash entering at the assumed temperature of 146° F. through pipe 96 is somewhat reduced in temperature by dilution with 110° F. slop as above described. In passing through the multi-tubes 95 of jackets 93, it is further cooled by the water of such jackets and leaves the heat exchanger through pipe 112 at a temperature of 66° F. to 68° F. enroute to the fermenters.

Cooling water used in the heat exchanger passes to the drain or to points of further use through pipe 110, above described, or through pipe 113, which is the discharge pipe from serially connected jackets 92.

Where it is desired to flush the multiple tubes of the heat exchanger parts with cold water, this may be done through the cross connection provided at 114 from the water supply line 100 to the slop inlet line 98, the cross connection being controlled by valve 115. The flushing water will be discharged either at 103 or 116, according to the setting of valves 104 and 117 respectively.

It will be understood that the foregoing is merely illustrative of a practical application of the invention to distillery usage, and that among the many other installations for which this type

of heat exchanger is adapted are textile mills, breweries, and the like.

It will further be obvious that any desired water and steam connections and thermometers, gauges, rate-of-flow controllers, meters and so forth can be added to the organizations disclosed.

What is claimed is:

1. In a heat exchanger, the combination with a plurality of jacket pipes closed at their ends and having lateral connections in series, of a plurality of tubes extending in parallel through each such jacket pipe and opening through said ends and provided externally of such pipes with tube-to-tube connections of substantially uniform cross section with the respective tubes, end jacket pipes in said series having end plates providing terminal mountings for the tubes within said pipes, and manifold fittings to said tubes externally of said jackets, said manifold fittings constituting the only substantial change in cross section of the passages formed by said tubes throughout the heat exchanger, supply and waste pipes having cross connections with said manifold fittings and connected therethrough with said tubes, and valves controlling said connections for placing either of said manifold fittings in direct communication with the supply pipe and either of said manifold fittings in direct communication with the waste pipe whereby flow through said tubes may be reversed to back wash the manifold fittings of the end jacket pipes.

2. The combination set forth in claim 1 in which the respective jacket pipe ends comprise plates in which ends of said tubes are positioned, said plates constituting closures for the respective pipes, the connection between the tubes comprising complementary plates and elbowed tubes having their ends mounted in the respective complementary plates, the said complementary plates being connected to the plates first mentioned in positions to register the ends of the elbowed tubes with the tube ends mounted in the plates first mentioned.

3. The combination set forth in claim 2 in which certain of said tube ends project from their respective plates and certain of said tube ends are countersunk in their respective plates in positions complementary to the said projecting tube ends to assist in maintaining the plates in registration and the tube ends in abutment.

4. A heat exchanger comprising a series of jacket pipes connected sequentially and provided internally with parallel tubes, fittings at the ends of the pipes constituting closures therefor and having the ends of the tubes mounted therein, complementary fittings connected with each of the fittings first mentioned, elbowed tubes at the ends of the respective pipes mounted in the complementary fittings and connecting certain of the tubes in the respective pipes with other tubes therein for flow forth and back through the tubes of the respective pipes, and other elbowed tubes at the opposite ends of the respective pipes connecting the ends of certain tubes of each pipe with the ends of certain tubes of another pipe whereby the tubes of the several pipes are connected in series.

5. In a device of the character described, the combination with a supply pipe and a waste pipe, of a heat exchanger comprising a series of jacket means, closures at the terminal ends of the terminal jackets, tube means extending in substantially uniform cross section throughout the series of jacket means to the closures, manifold fittings

connected to the respective closures, and valve controlled connections from each of said fittings to the supply pipe and the waste pipe whereby flow through said tubes and fittings is reversible, said jacket means having supply and delivery connections.

6. The device of claim 5 in which the valves controlling said connections are manually operable.

7. In a device of the character described, the combination with a supply pipe and a waste pipe, of a heat exchanger comprising jacket means, closures at the ends thereof, tube means extending in substantially uniform cross section through the jacket means to the closures, fittings connected to the respective closures, and valve controlled connections from each of said fittings to the supply pipe and the waste pipe whereby flow through said tubes and fittings is reversible, said jacket means having supply and delivery connections, the valves controlling said connections comprising time-controlled means including fluid pressure means interconnected with said time-controlled means for reversing flow through said fittings and tubes at predetermined intervals.

8. A device of the character described comprising the combination with jacket means provided with terminal closures and a plurality of parallel tubes of substantially uniform diameter providing continuous parallel communication through the jacket means between the closures, inlet and outlet connections for the jacket means, fittings connected with said jacket means and having communication through said closures with said tubes, supply and waste pipes having cross connections with the respective fittings and connected therethrough with said tubes, and valves controlling said connections for placing either of said fittings in direct communication with the supply pipe and either of said fittings in direct communication with the waste pipe, said valves being manually operable.

9. A device of the character described comprising the combination with jacket means provided with terminal closures and a plurality of parallel tubes of substantially uniform diameter providing continuous parallel communication through the jacket means between the closures, inlet and outlet connections for the jacket means, fittings connected with said jacket means and having communication through said closures with said tubes, supply and waste pipes having cross connections with the respective fittings and connected therethrough with said tubes, and valves controlling said connections for placing either of said fittings in direct communication with the supply pipe and either of said fittings in direct communication with the waste pipe, said valves comprising a power operator, and a time-switch having means interconnected with said power operator for the intermittent actuation of said operator in predetermined sequence to backwash said tubes and fittings.

10. The device of claim 9 in which said valves comprise a single rotatable plug having a plurality of passages therethrough and a casing having two inlets and two outlets with which said passages are alternately registerable in the rotation of said plug.

11. The combination with a heat exchanger comprising a plurality of jackets having inlets and outlets sequentially connected, of closures connected with the respective jackets, tubes having their ends mounted in said closures and extending in parallel through the respective

jackets, fittings communicating with said tubes at closures at the ends of the series of jackets, complementary fittings abutting the closures at the intermediate ends of the sequentially connected jackets and provided with elbowed tubes affording communication between the tubes of the jackets to which said complementary fittings are applied, the said tubes and elbowed tubes providing parallel conduits of substantially uniform cross section throughout the series of sequentially connected jackets, a supply pipe, a waste pipe, and a connection from each of said first mentioned fittings to each of said pipes, the said connections being valve controlled, the valve controlling said connections comprising a rotary plug valve having a pair of angularly offset passages and ports at substantially equal angular spacing and connected respectively with the supply pipe and one of said first mentioned fittings and the waste pipe and the other of said first mentioned fittings, in further combination with time-controlled switch, solenoid means and power operator interconnected with said solenoid means for the periodic oscillation of said valve plug for connecting the supply and waste pipes respectively with different fittings first mentioned, the periods being such that circulation through said tubes is largely in one direction with occasional reverse in direction whereby to back wash said fittings while maintaining circulation primarily in said one direction.

12. The device of claim 11 in which the several jackets are arranged in parallel tiers, the jackets at corresponding ends of the respective tiers being cross connected, and the tubes of such jackets being cross connected, the said valve being disposed between said tiers.

13. A heat exchanger installation in a laundry or the like having a hot water sump, a drain, a cold water supply line, and a cold water delivery

line, such installation comprising a set of jackets connected in series and communicating with said supply and delivery lines to provide a continuous conduit therebetween, parallel tubes in the respective jackets connected in series with each other and providing smooth-walled conduits of substantially uniform cross section from one end of said series of jackets to the other, manifold fittings communicating with the parallel tubes at each end of said series, and means providing valve controlled communication between each fitting and the sump and drain respectively, the valves controlling communication through said last mentioned means being operable to control flow from said sump to either of said fittings and thence through said tubes and the other of said fittings to the drain.

14. The device of claim 13 in which the several jackets are disposed with the first and last jacket in immediate proximity to each other, said valve controlled communication means comprising a four-way valve having ports communicating with the respective fittings and the drain and sump, said valve being disposed intermediate said first and last jacket.
